CLAMP FOR BOAT MOORING LINES OR THE LIKE

Robert R. Reay, 1799 Oxford St., Grosse Pointe Woods,
Mich. 48236

Filed Jan. 20, 1967, Ser. No. 5,495

Term of patent 14 years
(Cl. D54—11)

FIGURE 1 is a perspective view of a clamp for boat mooring lines or the like, showing my new design; and

FIGURE 2 is a perspective view of the clamp taken from the side opposite to FIGURE 1.

The broken lines are for illustrative purposes only.

I claim:

The ornamental design for a clamp for boat mooring lines or the like, as shown and described.
